CONTROL DEVICE

Edgar H. Ayers, Schenectady, N. Y., assignor to
 General Electric Company, a corporation of
 New York

Application July 1, 1941, Serial No. 400,632

18 Claims. (Cl. 200—83)

My invention relates to control devices and more particularly to refrigerator control devices, and has for its object a simple and reliable device provided with a single knob for adjusting the device for a desired refrigerator temperature and for adjusting the device to provide a high defrost temperature after which the control is returned to a normal operating condition, and in addition, to give a single cycle low temperature quick-freeze setting after which the control is returned to the normal operating condition.

More specifically, my invention relates to control devices utilizing over-center spring snapping means of the type described and claimed in Patent No. 1,921,126, issued on August 8, 1933, to Leonard P. Hutt. In carrying out my invention, I provide means operated by a single knob for temporarily moving the switch arm to predetermined positions for the defrost and quick freeze settings in which the position of the point of connection between the over-center operating spring and the switch arm is changed so as to require a larger or smaller movement of the operating member to produce snap action of the switch arm. After operation of the control at this high defrost or low quick freeze temperature, the latching means is disengaged forceably by the operation of the switch arm by the over-center spring.

For a more complete disclosure of my invention, reference should be had to the accompanying drawings in which Fig. 1 is a plan view of a control device having means for obtaining a defrost adjustment embodying my invention; Fig. 2 is a partly sectional view along the line 2—2 of Fig. 1 looking in the direction of the arrows; Fig. 3 is a view in perspective of the operating mechanism alone with certain parts distorted for purposes of clarity; Figs. 4 and 5 are fragmentary views of the stop means in the normal open and defrost open positions respectively; Fig. 6 is a perspective view similar to Fig. 3 showing a form of my invention providing for both defrost and quick freeze settings; Fig. 7 is a view similar to Fig. 6 showing a modified form of my invention having a defrost setting only; while Fig. 8 is an exploded view in perspective and partially in section of an operating knob embodying my invention.

Referring to the drawings, in one form of my invention I provide over-center spring snap operating means for the switching means comprising a switch arm 10 secured on a pivot 11 and provided with a flexible arm 12 carrying on its

end a movable contact 13 which cooperates with a stationary electric contact 14. This switch arm is actuated by an operating arm 15 having a pivot 16 and operated by a bellows temperature responsive device 17. The over-center spring connection between these two arms 10 and 15 comprises a U-shaped link 18 having its ends pivotally secured on a pivot 20 on the ends of two laterally extending projections 19 which are spaced apart and secured to the end of the operating arm 15. The cross or base portion 21 of the link is connected by an over-center helical tension spring 22 with a projection 22a on the end of the switch arm 10 and extending laterally therefrom. This projection 22a is positioned to move between the projections 19 upon relative movement between the two arms 10 and 15. Stops 24 and 25 are provided on opposite sides of the link 18 adjacent its closed movable end for the purpose of limiting the movement of this end.

In the operation of this over-center snap mechanism, the determining factor is the relative positions of the pivot 20 and the pivot 23 forming the connection between the spring 22 and the projection 22a. When the pivot 20 is below the pivot 23, as viewed in Fig. 1, the spring applies a force holding the link 18 against the upper stop 24 and a force to the arm 10 biasing it in a counterclockwise direction so as to hold the contact 13 in engagement with the contact 14. If now the arm 15 is raised, as viewed in Fig. 1, until the pivot 20 is slightly above the pivot 23, then the spring applies a component of force tending to move the link 18 clockwise about its pivot 20 into engagement with the lower stop 25. This, of course, changes the position of the end of the spring and thereby reverses its component applied to the arm 10. As seen in Fig. 1, the spring applies a force along a line passing through the pivot 23 and extending above the pivot 11. Soon after the link 18 begins to move downward the line of force of the spring moves below the pivot 11 whereby a counterclockwise torque is applied to the arm 10 and the arm is therefore snapped in a counterclockwise direction to its open circuit position.

In accordance with my invention, I provide means for temporarily moving the arm 10 to a position in which the position of the pivot 23 is changed thereby to vary the required amount of movement of the arm 15 to snap the switch arm to its open or closed circuit position, as the case may be. As a result, a higher or lower tempera-

ture is required to cause the bellows 17 to actuate the operating arm.

In the form of my invention shown in Fig. 1 I provide an extension 26 on the switch arm 10 extending laterally therefrom and downwardly, as viewed in Fig. 1. On its end this extension 26 is provided with a lateral extension 26a extending behind the bellows spring adjusting screw 27, as viewed in Figs. 1 and 2, where it is bent laterally downwardly to provide a portion 26b substantially parallel with the main portion 26 of the extension. This portion 26b extends through an aperture 28 provided for it in the enclosing casing 29 for the mechanism into cooperative relation with a knob 30 secured on the end of the adjustment screw 27. Thus by turning the knob 30 in a counterclockwise direction, as viewed in Fig. 3, an abutment or projection 31 on the knob is brought into engagement with the projection 26 and the projection is thereby moved toward the right hand, as seen in Figs. 1 and 3, whereby the switch arm 10 is moved in a counterclockwise direction about its pivot 11 to its open circuit position with the contact 13 disengaging the contact 14.

I provide resilient stop means for defining the position of the switch arm in this open circuit position. This stop means comprises a spring strip 32 secured to the portion 26a in lengthwise parallel relation therewith. Preferably, it is secured to the portion 26a at its lefthand end 33 as by riveting so that the remaining length of the strip is free to flex away from the portion 26a. The end of the strip 32 is moved to abut against a stop portion 34 provided by a bend in a spring strip member 35 when the knob 30 is turned to its extreme counterclockwise position. This is the defrost open position of the switch arm, although the knob must be moved back clockwise somewhat in order to free the end 26b and permit reclosure of the contacts by the bellows. Ordinarily, during normal operation of the device with the knob in an intermediate position, the end of the strip 32 abuts against the end portion 36 of the spring latching member 35 when the switch arm 10 is in its open circuit position, as shown in Fig. 4. The spring arm 35 thus limits or defines these normal and defrost open circuit positions.

When the knob 30 is thus turned to its extreme counterclockwise position, the strip 32 pushes the strip 35 aside toward the right hand, as viewed in Figs. 1 and 3, while at the same time the end of the strip 32 slides upward along the portion 36. Eventually the end of the strip 32 moves upward far enough to disengage the portion 36 and it then moves toward the right hand into engagement with the stop 34 on the strip 35 as seen in Fig. 5. The switch arm is now in a position in which the pivot 23 is lower, as seen in Fig. 1, than the normal open circuit position of the pivot and, therefore, the operating arm 15 must be moved downward a greater distance than normally in order to bring the pivot 20 below the pivot 23 and cause the link 18 to snap upward to the position shown in Fig. 1 for reclosure of the switch arm.

It will thus be observed that the spring 22 must be strong enough to snap the switch arm against the opposing force offered by the end of the strip 32 and force the end of the spring 32 over the shoulder 36a at the top of stop 36 back to the position of Fig. 4. In order to effect this the strip 32 is made much weaker than the snapping force applied by the spring 22. Also this is effected in part by the lengthwise engagement of the strip

32 with the portion 26a whereby flexure of the strip 32 in a downward direction as seen in Fig. 1 is limited mainly to the small portion projecting beyond the portion 26a. This portion is stiff enough to push the spring strip 35 away slightly with little bending of the strip 32 when the strip is moved to the defrost position of Fig. 5. This gives precision in the setting of the two parts for the defrost adjustment. On the other hand, the entire strip 32 is free to flex in moving from the position of Fig. 5 to the position of Fig. 4 and the strip is made fragile enough with respect to the spring 22 so that the strip readily bends.

Not only must the bellows compress the spring 37 farther from the defrost adjustment, but the operating arm 15 engages an auxiliary spring arm 38 mounted on the pivot 16 and biases against a stop 39 by a helical compression spring 40. This arm 38 has the projection 41 extending to a point near the arm 15 but normally not engaged by the arm 15. When the defrost setting is made, however, the arm 15 must be depressed far enough to engage the projection 41 and thereafter compress the auxiliary spring 40 in order to snap the switch arm to the closed position. This additional load of the spring 40 requires higher fluid pressures in the bellows and, consequently, a higher temperature for operation, which temperature is high enough to effect the defrosting of the evaporator.

It is contemplated that the bellows is responsive, through the usual closed tubular system containing an expansible fluid, to the temperature of the evaporator in a well known manner.

It will be understood that the adjustment screw 27 is provided with a coarse thread having sufficient pitch to give the desired range of adjustment of the bellows spring 37 in less than one complete revolution of the screw. It will be noted that the lower end of the spring 37 rests on a traveling seat 42 with which the screw is in threaded engagement. This seat is provided with two spaced prongs 43 (Fig. 3) which embrace a rib on the inner wall of the casing extending parallel with the screw whereby the seat is held against turning movement. Moreover, the pitch of the screw threads is preferably in such direction that movement of the knob for the defrost setting compresses the spring 37 to its fully compressed position although the spring pressure is relieved somewhat when the knob is turned back to release the projection 26b after making the defrost setting. The knob may be left, however, if desired, in its extreme counterclockwise position, in which position the contact arm 10 is held permanently in its open circuit position whereby operation of the refrigerator motor controlled by the contacts and cooling of the refrigerator is prevented.

As seen in Fig. 1, a suitable connection terminal 44 is provided for the stationary contact 14, the two being connected together by a suitable screw or rivet. Also, a connection screw 45 spaced from the screw 44 is provided for the movable contact 13. This terminal 45 is connected to a rigid electrical conductor 46 inside the casing which, in turn, is electrically connected by means of a flexible lead 47 to the contact arm 10.

In the form of my invention shown in Fig. 6 I have provided both a defrost setting and a quick freeze setting. Moreover, in this form of my invention these two settings are made by means of a plunger 50 which is carried on the knob 51. More specifically, the plunger 50 is pushed in to actuate the extension 52 on the switch arm to the defrosting position in which it is latched in the manner described in connection

with Figs. 1 to 5 inclusive by means of the spring latching members 53 and 54. The operating connection between the plunger 50 and the switch arm 52 is made by means of a disc 55 secured to the plunger 50 and being free to turn with the knob 51. This disc lies in a notch 56 in the end of the arm 52, the notch being several times wider than the disc so as to provide a limited freedom of movement. Thus the plunger 50 can be pressed to establish the defrost setting when the knob is in any angular position. When the plunger is pressed, the disc 55 engages the innermost edge of the notch 56. Also, if desired, the defrost setting can be cancelled by pulling the plunger out until the strip 52 is pulled off the latch strip 54 by engagement of the disc with the outermost edge of the slot 56.

The quick freeze adjustment is effected by pulling the plunger 50 out still farther, i. e., farther than required to cancel the defrost setting. This pulls the switch arm 52 outward, as seen in Fig. 6, and moves the switch arm about its pivot 57 in a clockwise direction slightly, whereby it becomes necessary for the operating arm 58 to be moved a greater distance clockwise about its pivot 59 in order to separate the contacts, and consequently the motor driving the refrigerator mechanism operates to reduce the refrigerator temperature to a still lower value until the bellows spring 60 overcomes the bellows and moves the operating arm 58 to operate the contacts.

The switch arm is held in this quick freeze position by means of an extension 61 secured to it and carrying at its end a resilient spring strip 62 which is similar to the spring strip 53. The end of this strip 62 normally, as shown in Fig. 6, rests in abutting relation against the end of a flexible spring contact arm 63 carrying a movable contact 64 on its end. During the quick freeze adjustment the end of the strip 62 moves toward the left hand, as seen in Fig. 6, moving the end of the contact arm 63 to one side until finally the end of the strip 62 slips over a latching shoulder 65 in the strip 63, against this offset longer portion as a stop. This is the quick freeze position.

It will be noted that in this form of the invention the movable contact is not secured directly on the arm 66, as shown in Fig. 1, but constitutes a separate arm 63 having one end secured to a fixed electrically conducting support 67. The normally stationary contact 68 is likewise on the end of a flexible arm 69 secured to an electrically conducting support 70. The supports 67 and 70 are secured in the electrically insulating casing described in connection with Fig. 1 and constitute means for connecting electric leads to the contacts 64 and 68. It will be understood that the arm 69 yields with the arm 63 when the quick freeze adjustment is being made.

It will be understood that the quick freeze adjustment, since it is for a lower temperature than prevailing at the time the adjustment is made, will effect the engagement of the contacts 64 and 68, if they are not already engaged, for operation of the refrigerator until a low temperature is reached. When the low temperature is reached, the over-center snapping spring 71 snaps the switch arm to its open circuit position and in doing so exerts enough force to forcefully pull the end of the strip 62 off the shoulder 65 and thereafter move the end of the strip 62 away from the contact arm 63 whereupon the contact arm moves its contact 64 out of engagement with the other contact to open the motor circuit. It will be understood that the contact arm 63 is shaped or

bent so as to normally assume a position with its contact 64 in spaced relation with the other contact.

In the form of my invention shown in Fig. 6 I have also provided two auxiliary loading springs 72 and 73 for applying additional spring forces for defrost and quick freeze respectively. Thus the spring 72 normally holds an arm 74 in the position shown about its pivot 75 with one projection 76 in engagement with a stop member 77. Another projection 78 of this arm 74 is in position to be engaged by the end of the operating arm 58 when it is depressed during defrosting and thereby applies an additional spring force to the operating arm as explained in connection with Figs. 1 to 5 inclusive.

Likewise, the quick freeze spring 73 holds an arm 79 in the position shown about the pivot 75 with one projection 80 in engagement with the stop 77 and another projection 81 in a predetermined position on the opposite side of the operating arm from the projection 78. Therefore, when the operating arm 58 is moved clockwise during quick freeze beyond its normal position for opening of the contacts, it engages the projection 81 and the pull of the spring 73 is applied to it. It will be noted that the spring 73 acts in opposition to the main bellows spring 60 in this case, thus reducing the effective spring force tending to move the operating arm clockwise. As a result, a lower temperature is required to separate the contacts.

Another feature of the springs 72 and 73 is that their two ends opposite their ends which are secured to the arms 74 and 79 are secured to an extension 83 carried by the seat member 84 from the spring 60. Thus, when the knob 51 is rotated to vary the pressure of the spring 60 and thus adjust the temperature maintained in the refrigerator, the pulls applied by the springs 72 and 73 to their arms are adjusted accordingly but in inverse relation to the adjustment of the compression spring 60. In other words, movement of the adjustment member 84 to compress the spring 60 and thereby increase the pressure applied by the spring 60 at the same time decreases the lengths of the tension springs 72 and 73 whereby the forces applied by them are decreased. This inverse adjustment of the springs 72 and 73 is such that the spring pressure opposing the operating arm 58 during defrost and quick freeze is always a substantially predetermined value regardless of the temperature setting of the refrigerator.

It will be observed, furthermore, that the disc 55 is provided with a radially extending projection 85 on its periphery which provides for an off position in which the contacts are permanently separated. This off position is obtained by turning the knob 51 substantially 180° from the position shown in Fig. 6 until the projection 85 engages the switch arm 52 and forces it to its open circuit position. Also, a notch 86 is provided in the disc 55 adjacent the projection 85 to facilitate the assembly of the parts, this notch being deep enough to permit the end of the switch arm 52 to be slipped through it to the position shown in Fig. 6.

The modified form of my invention shown in Fig. 7 is similar to the form shown in Figs. 1 to 5 inclusive in that an adjustment for defrost only is provided. It utilizes, however, the plunger 50 of Fig. 6 together with the adjustment disc 55. In this form of Fig. 7, also, the compensating spring 87 is secured to the adjustment member

88 for the main bellows spring 89. In this form, the other end of the spring is attached to an arm 90 pivotally mounted on a bracket 91 secured to the insulating casing enclosing the parts and normally held by the spring 87 against a stop 92. The other end 93 of the arm is engaged by the operating arm 94 during defrost, as will be understood from the description in connection with Fig. 6.

As shown in Fig. 8, the plunger 50 is provided with an internal opening for a helical compression spring 95 and with slots 96 and 97 in which loosely fit radially extending arms 98 and 99 on the knob 51. This arrangement secures against rotation the hub portion 100 of the knob to its outer cylindrical portion while providing for relative axial movement between the two. On the opposite side of the arms 98 and 99 from the plunger is a second compression centering spring 101, the other end of which bears on the disc 55. The disc is secured to the plunger by means of three connecting members 102, 103 and 104 extending laterally from the disc and spaced 120° apart. The ends of these members are T-shaped and lie in T-shaped slots 105 provided for them in the plunger. Thus the plunger is normally held in a predetermined central position by the springs 95 and 101 and may be pushed in or pulled out for predetermined distances.

While I have shown a particular embodiment of my invention, it will be understood, of course, that I do not wish to be limited thereto, since many modifications may be made and I, therefore, contemplate by the appended claims to cover any such modifications as fall within the true spirit and scope of my invention.

What I claim as new and desire to secure by Letters Patent of the United States, is:

1. A control device comprising a switch member, an operating member, a resilient connection between said members for moving said switch member quickly between an open circuit position and a closed circuit position upon a predetermined amount of movement of said operating member with respect to said switch member, stop means for normally limiting the movement of said switch member in one of said positions, means providing for movement of said switch member beyond said one position thereby to require a greater movement of said operating member to cause movement of said switch member, and resilient means engaged by said operating member when said operating member moves beyond said one position for increasing the required pressure by said operating member for operation of said switch member.

2. A control device comprising switching means, a switch member for operating said switching means, a temperature responsive operating member, a spring connection between said members for snapping said switch member between an open circuit position and a closed circuit position when said operating member is moved to predetermined positions with respect to said switch member in response to predetermined changes in temperature, stop means normally limiting the movement of said switch member in one of said positions, manually operated means for moving said switch member past said stop means thereby to require an increased movement of said operating member to snap said switch member to its other normal position, and resilient means engaged by said operating member during said increased movement of said operating member for increasing the required tem-

perature change for operation of said switch member.

3. A control device comprising a switch arm, a temperature responsive operating arm, an over-center snap spring, a pivot bearing on each of said arms, connections between said spring and said arms including said pivot bearings whereby the force of said spring is applied to said pivot bearings and the component of the force of said spring producing movement of said switch arm being reversed upon a predetermined amount of movement of said operating arm with respect to said switch arm thereby to move the pivot bearing on said operating arm from one side to the other of the pivot bearing on said switch arm, resilient stop means, a stop member on said switch arm normally engaging said stop means thereby to limit the movements of said switch arm to normal open circuit position, and manually operated means for engaging and moving said switch arm past said stop means beyond one of said positions thereby to require an increased change in the temperature of said operating arm for movement of its bearing to the other side of the bearing on said switch arm, said stop member thereafter engaging said stop means upon a subsequent movement of said switch arm in said open circuit direction thereby to limit the opening movement of said switch arm to a normal open circuit position.

4. A control device comprising a switch arm, a temperature responsive operating arm, an over-center snap spring, a pivot bearing on each of said arms, connections between said spring and said arms including said pivot bearings whereby the force of said spring is applied to said pivot bearings and the component of the force of said spring producing movement of said switch arm being reversed upon a predetermined amount of movement of said operating arm with respect to said switch arm thereby to move the pivot bearing on said operating arm from one side to the other of the pivot bearing on said switch arm, stop means for limiting the movements of said switch arm to normal open and closed circuit positions, and manually operated means for engaging and moving said switch arm past said stop means beyond one of said positions thereby to require an increased movement of said operating arm for movement of its bearing to the other side of the bearing on said switch arm, and loading means engaged by said operating arm during such increased movement of said operating member so as to increase the temperature change required for operation of said switch arm.

5. A control device comprising a switch member, a temperature responsive operating member, a spring forming an operating connection between said members thereby to snap said switch member between an open circuit position and a closed circuit position upon movement of said operating member in response to an increase in temperature, resilient stop means for limiting normally the movement of said switch member in one direction to a predetermined normal position, said stop means being arranged to yield to provide for movement of said switch member past said stop means beyond said normal position to an abnormal position in which increased movement of said operating member is required to snap said switch member to the other normal position, and a manually operated member for engaging and moving said switch member past said stop means to said abnormal position so that an increased movement of said operating member is

required to snap said switch member to its other normal position, said switch member thereafter engaging said stop means upon a subsequent movement of said switch member in said one direction.

6. A control device comprising a switch member, a temperature responsive operating member, a spring forming an operating connection between said members thereby to snap said switch member between an open circuit position and a closed circuit position upon movement of said operating member in response to an increase in temperature, resilient stop means for limiting normally the movement of said switch member in one direction to a predetermined normal position, said stop means being arranged to yield to provide for movement of said switch member beyond said normal position to an abnormal position in which increased movement of said operating member is required to snap said switch member to the other normal position, a spring opposing movement of said operating member, a manually operated member for varying the force applied by said spring, means operated by said manually operated member for engaging and moving said switch member past said stop means to said abnormal position, and auxiliary spring means engaged by said operating member when said operating member is moved through said increased movement to snap said switch member from said abnormal position to the other normal position.

7. A refrigerator control device comprising a switch member, a temperature responsive operating member, a spring forming an operating connection between said members thereby to snap said switch member between an open circuit position and a closed circuit position upon movement of said operating member in response to an increase in temperature, resilient stop means for limiting normally the movement of said switch member in an open circuit direction to a predetermined normal open circuit position, said stop means being arranged to yield to provide for movement of said switch member beyond said normal open circuit position to an abnormal open circuit position in which increased movement of said operating member is required to snap said switch member to said closed circuit position, a spring opposing movement of said operating member in response to an increase in temperature, a manually operated member for varying the force applied by said spring, means operated by said manually operated member for engaging and moving said switch member past said stop means to said abnormal position when said manually operated member is moved to a position of increased spring force, and auxiliary spring means engaged by said operating member when said operating member is moved through said increased movement to snap said switch member from said abnormal open position to said closed circuit position.

8. A control device comprising a switch member, a temperature responsive operating member, a spring forming an operating connection between said members for causing said switch member to snap between normal closed and normal open circuit positions upon movement of said operating member, resilient stop means for limiting selectively the movement of said switch member in one direction to one of said normal positions and to an abnormal position beyond said normal position, a spring opposing movement of said operating member, a knob connected to vary

the force applied by said spring upon rotation of said knob, means operated by said knob when said knob is turned to a predetermined position for moving said switch member to said abnormal position, and auxiliary spring means engaged by said operating member when said operating member is moved to snap said switch member from said abnormal position.

9. A control device comprising a switch member, a temperature responsive operating member, a spring forming an operating connection between said members for causing said switch member to snap between closed and open circuit positions upon movement of said operating member, stop means for limiting selectively the movement of said switch member to a normal open circuit position and an abnormal open circuit position, a spring opposing movement of said operating member in response to an increase in temperature, an adjustment member connected to vary the force applied by said spring upon rotation of said adjustment member, a projection on said adjustment member, an extension on said switch member in position to be engaged by said projection when said adjustment member is turned to a position of maximum force applied by said spring thereby to snap said switch member to said abnormal open position.

10. A control device comprising a switch member, a temperature responsive operating member, a spring forming an operating connection between said members for causing said switch member to snap from an open to a closed circuit position upon movement of said operating member in response to an increase in temperature, resilient stop means for limiting selectively the open circuit position of said switch member to a normal open circuit position and an abnormal open circuit position, a spring opposing movement of said operating member in response to an increase in temperature, a knob connected to vary the force applied by said spring upon rotation of said knob, a projection operated by said knob, an extension on said switch member in position to be engaged by said projection when said knob is turned to a position of maximum force applied by said spring thereby to move said switch member to said abnormal open position, and auxiliary spring means engaged by said operating member when said operating member is moved to snap said switch member from said abnormal open position to said closed circuit position.

11. A refrigerator control device comprising switching means, a switch arm for operating said switching means, a temperature responsive operating arm, an over-center spring forming an operating connection between said arms for causing said switch arm to snap between closed and open circuit positions upon movement of said operating arm, resilient stop means for limiting normally the movement of said switch arm to a normal open circuit position and yielding to provide for continued movement of said switch arm to a defrost open position, a spring opposing movement of said operating arm in response to an increase in temperature, a knob connected to vary the force applied by said spring upon rotation of said knob, a projection on said knob, an extension on said switch arm in position to be engaged by said projection when said knob is turned to a position of maximum force applied by said spring thereby to snap said switch arm to said defrost open position, and auxiliary spring pressed means engaged by said operating arm when said arm moves to snap said switch arm from said

defrost open position to said closed circuit position.

12. A refrigerator control device comprising switching means, a switch arm for operating said switching means, a temperature responsive operating arm, a link pivoted on the end of one of said arms, an over-center tension spring connecting the movable end of said link with the end of the other of said arms, stops for limiting the movement of said link so that movement of said operating arm in response to temperature causes said link to snap from one position to another and thereby actuate said switch arm between closed and open circuit positions, resilient stop means for limiting normally the movement of said switch arm by said spring to a normal open circuit position and yielding to provide for continued movement of said switch arm to a defrost open position, a spring opposing movement of said operating arm in response to an increase in temperature, a knob connected to vary the force applied by said spring upon rotation of said knob, a projection on said knob, an extension on said switch arm in position to be engaged by said projection when said knob is turned to a position of increased force applied by said spring thereby to move said switch arm to said defrost open position whereby said link is snapped to its open circuit position, and auxiliary spring pressed means engaged by said operating arm when said arm moves to snap said link and said switch arm to their closed circuit positions.

13. A refrigerator control device comprising a switch member, a temperature responsive operating member, a spring forming an operating connection between said members thereby to snap said switch member between an open circuit position and a closed circuit position upon movement of said operating member in response to an increase in temperature, resilient stop means for limiting normally the movement of said switch member in each direction to predetermined normal open circuit and closed circuit positions, said stop means being arranged to yield to provide for movement of said switch member beyond each of said normal positions to an abnormal position in which increased movement of said operating member is required to snap said switch member to its other normal position, a spring opposing movement of said operating member, manually operated means for varying the force applied by said spring and for moving said switch member to either one of said abnormal positions.

14. A refrigerator control device comprising a switch member, a temperature responsive operating member, a spring forming an operating connection between said members thereby to snap said switch member between an open circuit position and a closed circuit position upon movement of said operating member in response to changes in temperature, resilient stop means for limiting normally the movement of said switch member in each direction to predetermined normal open circuit and closed circuit positions, said stop means being arranged to yield to provide for movement of said switch member beyond each of said normal positions to an abnormal position in which increased movement of said operating member is required to snap said switch member to its other normal position, a spring opposing movement of said operating member, manually operated means for varying the force applied by said spring and for moving said switch member to either one of said abnormal positions, and auxiliary spring means engaged by said operating

member when said operating member is moved to snap said switch member from either one of said abnormal positions.

15. A refrigerator control device comprising a switch member, a temperature responsive operating member, a spring forming an operating connection between said members thereby to snap said switch member between an open circuit position and a closed circuit position upon movement of said operating member in response to changes in temperature, resilient stop means for limiting normally the movement of said switch member in each direction to predetermined normal open circuit and closed circuit positions, said stop means being arranged to yield to provide for movement of said switch member beyond each of said normal positions to an abnormal position in which increased movement of said operating member is required to snap said switch member to its other normal position, a spring opposing movement of said operating member, a knob connected to vary the force applied by said spring upon rotation of said knob, a plunger mounted on said knob for movement independently of said knob selectively inward or outward, and an operating connection between said plunger and said switch member providing for rotation of said plunger with said knob and for movement of said switch member to said abnormal positions selectively upon inward or outward movement of said plunger.

16. A refrigerator control device comprising a switch member, a temperature responsive operating member, a spring forming an operating connection between said members thereby to snap said switch member between an open circuit position and a closed circuit position upon movement of said operating member in response to changes in its temperature, resilient stop means for limiting normally the movement of said switch member in each direction to predetermined normal open circuit and closed circuit positions, said stop means being arranged to yield to provide for movement of said switch member beyond each of said normal positions to an abnormal position in which increased movement of said operating member is required to snap said switch member to its other normal position, a spring opposing movement of said operating member, a knob connected to vary the force applied to said spring upon rotation of said knob, a plunger mounted on said knob for movement independently of said knob selectively inward or outward, an operating connection between said plunger and said switch member providing for rotation of said plunger with said knob and for movement of said switch member to said abnormal positions selectively upon inward or outward movement of said plunger, and auxiliary spring means engaged by said operating member when said operating member is moved to snap said switch member from either one of said abnormal positions, thereby to require abnormally high and low temperatures of said operating member for operation of said switch member from either one of said abnormal positions.

17. A control device comprising a switch member mounted for movement between two positions, first and second stops spaced apart in the direction of movement of said switch member, a third stop on said switch member for engaging said first stop upon movement of said switch member in one direction thereby to limit the position of said switch member to a predetermined normal first position, temperature responsive

means, an operating connection between said temperature responsive means and said switch member requiring movement of said temperature responsive means varying in amount with the position of said switch member in said one direction in order to move said switch member from said first position to the other of its positions, a resilient mounting for at least one of said first and third stops, and a manually operated member movable to forcibly move said third stop past said first stop into engagement with said second stop whereby said switch member is given an abnormally great movement in said one direction requiring an abnormally great movement of said temperature responsive means to move said switch member to its other position, said third stop thereafter engaging said first stop upon a subsequent movement of said switch member in said one direction.

18. A control device comprising a switch member movable between open circuit and closed circuit positions, two stops spaced apart in the direction of movement of said switch member, a resilient extension on said switch member for

engaging upon opening movement of said switch member a nearer one of said stops thereby to limit the open circuit position of said switch member to a predetermined normal position, 5 temperature responsive means, an operating connection between said temperature responsive means and said switch member requiring movement of said temperature responsive means varying in amount with the open circuit movement of said switch member in order to move said switch member to its closed circuit position, and a manually operated member movable to engage and forcibly move said resilient extension past said nearer stop into engagement with the other 10 of said stops whereby said switch member is given an abnormally great movement in said open circuit direction requiring an abnormally great movement of said temperature responsive means to move said switch member to its closed circuit position, whereupon said resilient extension resumes its normal shape to engage said nearer stop upon a subsequent opening movement of 15 20 said switch member.
